COMPRESSOR

Ernest R. Huntley, Los Angeles, Calif., assignor
to Leo M. Harvey, La Canada, Calif.

Application January 15, 1940, Serial No. 313,890

24 Claims. (Cl. 230—108)

This invention relates to apparatus for the compression or evacuation of gases and relates more particularly to a compressor or vacuum pump of the centrifugal type. A general object of this invention is to provide a practical, effective compressor that is highly efficient, requiring a minimum of power for its operation.

Compressors and vacuum pumps have been introduced in which a liquid such as oil or water is subjected to centrifugal action and in which gas is entrained in the liquid so that the liquid acts as the compressing agent. Such prior devices employ various means for causing the gas to be entrained in the liquid so that it is carried outwardly to the periphery of the impeller wheel to be subjected to a pressure equal to the centrifugal pressure on the liquid at the point of discharge from the impeller. In such devices practically all of the power consumed is represented by the energy required to accelerate the fluid from the peripheral velocity at the point of intake of the impeller wheel to the velocity at the point of discharge from the impeller wheel. The liquid discharging from the impeller wheel of such a device is theoretically capable of doing substantially as much work as the work done in accelerating the liquid to the velocity of discharge. This work or energy in the liquid discharging from the impeller wheel is not efficiently utilized in the prior devices but is wasted or expended for no useful purpose. The prior devices do not embody effective means for proportioning the liquid and gas handled by the impeller wheel and a large part of the energy used in accelerating the liquid handled by the impeller wheel is wasted. For these reasons the prior devices of the character referred to are extremely inefficient and, therefore, expensive to operate.

Another and important object of this invention is to provide a compressor or vacuum pump of the centrifugal type mentioned above embodying a novel and highly efficient means for utilizing the energy in the heavy fluid or liquid discharging from the impeller wheel to promote efficient operation and reduce the cost of operation. The energy or a substantial portion of the energy in the rapidly rotating mass of heavy liquid leaving the rotary element of the present invention is utilized to assist in rotating the impeller thereby greatly reducing the power required to drive the compressor.

Another object of this invention is to provide a device of the character mentioned embodying a rotating element or impeller receiving the liquid and the gas at its interior and discharging the

fluid at its periphery, and a rotatable casing enclosing the impeller arranged to be driven by the liquid leaving the periphery of the impeller and having a driving connection with the impeller to assist in rotating the same. The casing embodied in the device of this invention is driven or rotated by the fluid put into motion by the impeller and is geared or otherwise connected with the impeller to assist in rotating the same, thus reducing the power necessary to drive the device. The casing rotates in the same direction as the impeller thereby practically eliminating the high fluid friction losses present in prior devices of this type embodying stationary casings for the impellers.

Another object of this invention is to provide a compressor of the character mentioned in which the liquid employed as the compressing agent is used over and over again or repeatedly recirculated.

Another object of this invention is to provide a compressor of the character mentioned embodying novel means for maintaining the fluid in the compression member in continuous motion thus eliminating the energy loss that occurs in most devices of this nature where the fluid must at some point pass through a port or nozzle in a stationary part and again be put into rotary motion by the impeller.

Another object of this invention is to provide a compressor of the character mentioned embodying novel and effective means for removing the heat of compression from the compressing liquid without interfering with or stopping the above-mentioned continuous circulation of the fluid in the compressor.

Another object of this invention is to provide a compressor of the character mentioned in which the drive between the impeller and the rotating casing provides a differential in the speed of rotation of the impeller and casing thereby setting up a differential in the pressures on the fluid in said passages, etc. to induce a continuous flow of the heavy fluid or liquid from its point of discharge from the impeller back to its point of delivery to the impeller.

Another object of this invention is to provide a compressor of the character mentioned embodying a novel port member that rotates with the rotatable casing and which serves to alternately admit quantities of the gas and liquid to the intakes of the impeller vanes or passages while rotating in the same direction as the impeller but at a slower speed so that the slugs or charges of liquid leaving the rotating port mem-

ber are picked up by the rotating impeller with a minimum of shock and little or no loss of energy.

Another object of this invention is to provide a compressor of the character mentioned in which the fluid discharges from the impeller at a substantial distance from the intake openings of the impeller assuring a large capacity operation in a compressor of small size.

The various objects and features of my invention will be fully understood from the following detailed description of typical preferred forms and applications of the invention, throughout which description reference is made to the following drawings, in which:

Fig. 1 is a central vertical detailed sectional view of one form of compressor of the invention showing a part of the driving motor and other elements in side elevation. Figs. 2 and 3 are fragmentary horizontal detailed sectional views taken substantially as indicated by lines 2-2 and 3-3, respectively, on Fig. 1. Fig. 4 is a fragmentary vertical detailed sectional view taken as indicated by line 4-4 on Fig. 2. Fig. 5 is a fragmentary horizontal detailed sectional view of another form of the invention, being a view taken as indicated by line 5-5 on Fig. 6. Fig. 6 is a central, vertical, detailed sectional view of the said other form of the invention, and Fig. 7 is a central, vertical, detailed sectional view of still another form of the invention.

The compressor or vacuum pump of the invention illustrated in Figs. 1 to 4, inclusive, of the drawings, may be said to comprise, generally, a housing 10, a rotary element or impeller 11 in the housing 10, a casing 12 rotatably supported in the housing 10 and enclosing the impeller 11, a port member 13 rotatable with the casing 12 and delivering liquid and gas to the impeller 11, a drive 14 between the casing 12 and the impeller 11, a cooling system 15 for cooling the compressing liquid employed in the casing 12, and port and conduit systems for handling the liquid and gas, the details of which will be later described.

The housing 10 contains the impeller 11, the casing 12 and the other active parts of the compressor. In the construction illustrated the casing 10 comprises a base 16 having a horizontal wall 17 spaced between its ends and a main housing member 18 supported on the base. Assuming the compressor to be positioned as illustrated in the drawings, the main housing member 18 is of inverted cup-shape and has a flange 19 on its lower edge secured to the upper end of the base 16 by screws 20. The drive means or power means for operating the compressor may be mounted on the member 18. A rather large opening 21 is formed in the upper wall of the housing member 18 and an electric motor 22 or other power means may be secured to the upper end of the member 18 by screws 23 to close the opening 21. It will be observed that the base 16, the member 18 and the motor 22 define a sealed chamber 24 that may contain the gas to be compressed. I have shown a pipe 25 communicating with the upper portion of the chamber 24 and leading to the atmosphere or to a supply of the gas to be compressed. If the device is to be employed as a vacuum pump the pipe 25 may lead to the space to be evacuated.

The horizontal wall 17 of the base member 16 has a central depression 26 surrounded by an upstanding annular wall 27. A boss 28 projects downwardly from the wall 17 and has a central socket 29 communicating with the lower end of

the depression 26. A central opening 30 enters the boss 28 from its lower end and a plug 31 closes the lower end of the opening 30. An outlet pipe or discharge pipe 32 communicates with the opening 33. A check valve 33 is preferably connected in the pipe 32 to prevent the return flow of the compressed gas when the compressor is idle. The housing 10 forms the principal stationary element of the device and the base 16 may be suitably fixed.

The rotary element or impeller 11 is supported in the housing 10 for rotation about a central vertical axis. The construction of the impeller 11 may be varied considerably without departing from the broader aspects of the invention. In the construction illustrated the impeller 11 has a central hub 34 and a disc-like main part 35 of enlarged diameter on the upper end portion of the hub 34. The impeller hub 34 is connected with the shaft 36 of the motor 32 to be driven by the motor. In the arrangement illustrated the hub 34 has an opening 37 in its upper end receiving the motor shaft 36. A flanged nut 38 is threaded or otherwise secured to the hub 34 and a collar 39 is pinned or otherwise fixed to the motor shaft 36 to oppose the nut 38. Axial pins 40 project from the collar 39 and are loosely received in openings 41 in the nut 38 to provide for the transmission of rotation between the motor shaft 36 and the impeller 11. A longitudinal opening 42 enters the hub 34 from its lower end and a tubular shaft 43 is force-fitted or otherwise fixed in the opening 42. The shaft 43 projects downwardly from the hub 34 and passes through the depression 26 and the socket 29 to enter the opening 30. A suitable antifriction bearing 44 is seated in the socket 29 to rotatably support the shaft 43 and the impeller 11. The tubular shaft 43 forms a conduit for the compressed gas as will be later described, and means is provided in the boss 28 for sealing about the shaft 43. This means may include packing 45 seated in the opening 30 and a coiled spring 46 under compression between the plug 31 and the packing 45 to hold the packing compressed.

The enlarged upper portion 35 of the impeller 11 is proportioned to have its periphery spaced a considerable distance inwardly from the wall of the housing 10 and preferably has a flat underside provided with a circular downwardly facing annular socket 47. The impeller vanes or the compression passages for handling the fluid when it is subjected to the centrifugal action may be provided in a circular or annular part 48 secured to the under side of the part 35. The part 48 is arranged to have its inner surface at the peripheral wall of the socket 47 and to have its periphery adjacent the periphery of the part 35. Pins or rivets 49 may serve to secure the part 48 to the part 35. The part 48 is provided with a multiplicity of circumferentially spaced compression passages 50. The passages 50 are equally circumferentially spaced and are of the same size or capacity. The lower sides of the passages 50 are closed by an integral wall of the part 48 and the impeller part 35 closes the upper sides of the passages. The passages 50 are preferably pitched outwardly and rearwardly relative to the direction of rotation of the impeller 11.

The impeller part 48 is further provided with spaced peripheral pockets 51 for receiving the compressed gas. The pockets 51 are spaced between the discharge ends of the spaced passages

50. The pockets 51 extend axially and their upper ends are closed by the part 35. Ports 52 extend inwardly in the part 48 from the trailing sides of the pockets 51 and lead to vertical or axial ports 53. The ports 53 extend upwardly to the upper side of the part 35 where they communicate with an annular chamber 54. The annular chamber 54 may be defined by a ring 55 of reclining L-shaped cross section secured to the upper side of the member 35. The inner ends of the radial ports 52 slope or curve upwardly and inwardly toward the ports 53 to assist in directing the fluid to the ports 53. The centrifugal action assures a complete separation of the gas and liquid in the annular chamber 54. Radial ports 56 are provided in the impeller part 35 and lead inwardly from the chamber 54 to the opening 42. The inner end of the tubular shaft 43 communicates with the inner portion of the opening 42 and the gas under pressure is free to pass longitudinally through the shaft 43 to the opening 30 and thence through the discharge pipe 32. Longitudinally spaced annular flanges 57 are provided on the periphery of the impeller 11 to assist in directing the gas to the pockets 51 as the fluid leaves the compression passages 50. One flange 57 may be formed on the impeller part 35 and the other may be formed on the part 48. The opposing sides of the flanges 57 are outwardly divergent.

The casing 12 is rotatably supported in the housing 10 to enclose the impeller 11. The casing 12 is a hollow structure comprising a generally cylindrical cup-like section 58 and a plate 59 closing the upper end of the section. The impeller 11 is arranged within the section 58 and the plate 59 extends across the upper end of the impeller with clearance. Screws 60 may serve to attach the plate 59 to the section 58. The section 58 has an opening 61 passing the shaft 43 with clearance and a suitable anti-friction bearing 62 is set in the opening 61 to assist in rotatably supporting the casing. The plate 59 has a central opening 63 receiving the upper portion of the hub 34 with clearance and an anti-friction bearing 64 is seated on the hub and is received in the opening 63 to assist in rotatably supporting the casing.

The casing 12 provides a substantially closed chamber 65 in which the rotating impeller 11 operates. It is to be noted that the casing 12 is supported for free or independent rotation. The casing 12 is proportioned so that the periphery of the impeller 11 is spaced from its interior and the upper and lower ends of the impeller are suitably spaced from the end walls of the casing. The casing 12 of course has suitable clearance in the stationary housing 10. A boss 66 is formed on the lower end of the casing section 58 below the bearing 62. The casing 12 is ported, as will be later described.

The port member 13 is provided to deliver or discharge the liquid and gas into the passages 50 of the impeller 11. The port member 13 rotates with the casing 12 and may be attached to or may form a part of the casing. In the preferred construction the member 13 surrounds the hub 34 of the impeller 11 with considerable clearance, leaving an annular space 67 around the hub. As illustrated, the member 13 is a generally cylindrical part whose periphery has cooperation with the internal surface of the impeller part 48. A disc-like enlargement 68 is provided on the lower end of the member 13 and

rests on the lower wall of the casing section 58. Screws 69 may secure the port member 13 to the section 58. The enlargement 68 has substantial clearance with the under side of the impeller part 48 leaving an annular space 70 which communicates with the outer portion of the casing chamber 68. The enlargement 68 may be of substantially the same diameter as the flanges 51 of the impeller 11. 10. The periphery of the port member 13 has a plurality of axially extending circumferentially spaced liquid ports 72 and a plurality of circumferentially spaced axially extending gas ports 73. The gas ports 73 may be smaller in capacity than the ports 72 and are spaced between the ports. The ports 72 and 73 extend between the upper and lower ends of the port member 13 and are open at the periphery of the member to discharge into the passages 50 of the impeller 11. 15. Radial ports 74 communicate with the lower ends of the ports 72 and extend outwardly through the enlargement 68 to the periphery of the enlargement. The ports 74 serve to circulate the fluid or liquid from the peripheral portion of the chamber 65 inwardly to the ports 72. The differential in pressures resulting from the centrifugal action assures the circulation of the fluid through the ports 74. With the device in operation there is a continuous circulation of liquid from the ports 72 through the passages 50 of the rotating impeller 11 to the peripheral portion of the chamber 65 and then back through the ports 74 to the ports 72.

30. A plate 75 is attached to the upper end of the port member 13 to close the upper ends of the liquid ports 72. The plate 75 has openings 75^a placing the upper ends of the gas ports 73 in communication with the annular socket 47 in the upper wall of the impeller 11. One or more ports 76 in the upper impeller part 35 communicate with the socket 47 so that the upper ends of the gas ports 73 are maintained in communication with the upper end of the casing chamber 65. One or more ports 77 are provided in the cover plate 59 of the casing 12 to maintain the upper portion of the casing chamber 65 in communication with the upper part of the housing chamber 24. Air or gas admitted to the housing chamber 24 by the pipe 25 is drawn through the ports 77 into the upper portion of the casing chamber 65 and is drawn from the chamber 65 through the ports 76 into the ports 73 in the rotating port member 13.

55. With the compressor provided with the gas port system described above the gas from the pipe 25 reaches the ports 73 and slugs or portions of the gas are delivered to the passages 50 in the rotating impeller to be entrained with the liquid admitted by the ports 72. The gas thus entrained with the liquid is subjected to compression by the centrifugal forces acting on the liquid in the passages 50 and upon leaving the periphery of the impeller the compressed gas is received in the pockets 51 and flows through the ports 52 and 53 to discharge into the chamber 54. From the chamber 54 the compressed gas passes through the ports 56, the tubular shaft 43 and the opening 30 to the discharge pipe 32. It will be seen that there is a continuous circulation of gas from the pipe 25 to the discharge pipe 32, the gas discharging under an increased pressure. It is important to note that the liquid employed as the compressing medium is continuously recirculated through the impeller 11 while the gas is being

drawn in and discharged under increased pressure.

The drive 14 between the casing 12 and the impeller 11 transmits movement and power from the casing to the impeller so that the energy expended by the fluid discharging from the impeller 11 is utilized to assist in rotating the impeller 11. In accordance with the invention the drive 14 is a differential drive restraining the casing 12 to rotate at a slower speed than the impeller 11 so that the fluid discharging from the impeller is effective in producing rotation of the casing 12 and so that the ports 72 and 73 alternately discharge into the impeller passages 50. The differential drive 14 may, of course, be varied considerably in character.

In the construction illustrated the drive 14 comprises a pinion 78 keyed or otherwise fixed to the casing boss 66 and a larger gear 79 keyed or otherwise fixed to the shaft 43 of the impeller 11. A vertical stub shaft 80 is fixed to the lower wall 17 of the housing 10 to project upwardly in parallel relation to the shaft 43. A pair of connected gears 81 and 82 is rotatable on the shaft 80. The gear 81 meshes with the pinion 78 while the gear 82 meshes with the gear 79. It will be seen that the gearing just described constitutes a differential drive for transmitting rotation from the casing 12 to the impeller 11.

The means 15 serves to remove or reduce the heat of compression by continuously subjecting a stream of the compressing medium or liquid to a cooling action. The lower portion of the housing 10 below the casing 12 and surrounding the wall 21 constitutes a basin or reservoir 83 for the liquid and a cooling coil 84 is arranged in this reservoir. A pipe 85 delivers a suitable cooling medium to one end of the coil 84 and a similar pipe 86 conducts the cooling medium from the other end of the coil.

The invention includes a novel duct system for circulating the compressing liquid to and from the cooling reservoir 83. Vertical or axial ports 87 are provided in the port member 13 and notches 88 in the member 13 connect the upper ends of the ports 87 with the liquid discharge ports 72. The upper inner portions of the ports 72 are the warmest parts of the device so that the ports 87 receive or carry away the liquid of the highest temperature. The lower ends of the ports 87 communicate with ports 89 formed in the lower wall of the case section 58. The lower wall of the section 58 has a downwardly and outwardly sloping surface 90 terminating in an abrupt annular shoulder 91. The liquid discharges from the ports 89 at the surface 90 and centrifugal force carries the liquid outwardly on the surface to the shoulder 91 where it discharges into the reservoir 83. The case contains sufficient liquid to maintain a level above the upper impeller flange 57 and a small stream of liquid continuously discharges through the ports 89 to fall to the cooling reservoir 83.

Radial ports 92 lead from the bottom of the reservoir 83 to the socket 29. The gear 79 is provided at its lower end with an apron 93 and a ported member 94 is arranged in the socket 29 to conduct the liquid from the ports 92 to the interior of the apron 93. The lower end of the pinion 78 is provided with an annular skirt 95. Ports 96 extend longitudinally through the gear 79 to conduct the liquid from the interior of the apron 93 to the interior of the skirt 95. Axial ports 97 extend through the pinion 78 and conduct the liquid from the interior of the skirt 95

to ports 98 in the lower wall of the case section 58. The ports 98 deliver the cooled liquid to the annular space 67 in the port member 13. It will be observed that the ports in the member 94 and the ports 96 and 97 are spaced varying or increased distances from the axis of rotation of the impeller 11 and the case 12 and centrifugal force causes the liquid to advance through the series of ports into the space 67. Narrow passages 99 extend tangentially through the port member 13 from the space 67 to the periphery of the member. The passages 99 discharge portions of the cooled liquid into the passages 50 of the rotating impeller 11. A tubular normally closed fitting 100 may be provided on the base 10 to facilitate the delivery of liquid to the reservoir 83. In practice the compressor will operate for a prolonged period before required additional liquid.

In operation, the motor 22 directly drives the impeller 11 and the impeller rotating within the casing 12 subjects the fluid in its passages 50 to centrifugal action. The fluid discharging from the periphery of the impeller 11 at a high velocity serves to rotate the casing 12. The liquid discharging from the impeller at a high velocity is capable of giving up the same amount of energy as that required to accelerate it to this velocity. In the device of the invention the energy represented by the rapidly rotating mass of liquid must be absorbed or utilized in rotating the casing, there being no other way of absorbing this energy. It follows then that where the casing is made to rotate at a slower speed than the impeller, by the differential gearing 14, all of this energy is transmitted back to the driving shaft 36 with no loss of energy other than that represented in the heat dissipated, the friction in the bearings and gearing and the friction loss in the fluid flowing diametrically into and out of the impeller. Thus the casing 12 is made to rotate in the same direction as the impeller 11 through the action of the compressing fluid discharging from the impeller.

The differential drive 14 transmits the rotary motion from the casing 12 to the impeller 11, so that the energy given up by the liquid in turning the casing 12 assists in rotating the impeller 11, and causes the casing to rotate at a slower speed than the impeller. Because of this differential in the speed of rotation, the passages 50 of the impeller 11 move into and out of receiving communication with the spaced ports 22 and 23 in the member 13. Thus the passages 50 alternately receive definite charges of liquid and definite charges of the gas and these charges move out through the passages 50 to discharge from the impeller at a greatly increased velocity. The compressing medium or liquid leaving the impeller 11 under an increased pressure flows back or rearwardly through the passages 74 to the ports 72 and the liquid is thus continuously recirculated through the impeller. This recirculation of the compressing medium is effected with practically no loss of energy, the energy represented by the rotating mass of the discharged compressing medium being transmitted to the driving shaft 36 as described above.

The gas discharging from the outer ends of the passages 50 under an increased pressure is received by the pockets 51 and flows through the ports 52 and 53 to the chamber 54. The final separation of the gas and liquid takes place in the chamber 54. The compressed gas flows through the ports 56, the shaft 43, and the open-

ing 30 to discharge from the pipe 32. The gas handled or compressed by the device is received from the chamber 24 of the housing 10 and may be supplied to the housing by the pipe 25. The gas passes through the ports 71 and 76 to the chamber 74 and enters the upper ends of the ports 73 to be picked up by the rapidly rotating impeller 11. Where the compressor is provided with the cooling system described above a portion of the heated compressing medium or liquid continuously flows through the ports 87 and 89 to discharge into the reservoir 83 where it gives up a portion of its heat. The cooled liquid flows through the ports 92, the port member 94 and the ports 96, 97 and 98 to the space 67 and re-enters the active part of the compressor through the passages 99. This cooled liquid continuously supplied to the compressor keeps the temperature of the compressor down.

Figs. 5 and 6 of the drawings illustrate a form of the invention embodying a simple inexpensive impeller 11^a and a form of structure that is designed to handle a constant flow of liquid to produce the compressing action. The structure illustrated in Figs. 5 and 6 may be said to comprise, generally, a housing 10^a, the impeller 11^a rotatable in the housing 10^a, a casing 12^a rotatable in the housing 10^a and enclosing the impeller 11^a, a drive 14^a between the casing 12^a and the impeller 11^a and fluid handling systems to be later described.

The housing 10^a may be substantially the same as the housing 10 comprising a base 16^a and an upper member 18^a. The base 16^a and member 18^a provide a chamber 24^a in which the casing 12^a rotates. A central depression 26^a is provided in the base 16^a and an upstanding annular wall 27^a is provided in the bottom of the depression. The motor 22^a for driving the compressor may close the upper end of the housing member 18^a.

The impeller 11^a comprises a hub 34^a and an enlargement or disc-like part 35^a projecting from the upper portion of the hub 34^a. The hub 34^a has a central opening 42^a that receives a tubular shaft 43^a. The shaft 43^a is fixed in the opening 42^a. A bearing 44^a in the bottom of the depression 26^a rotatably carries the shaft 43^a. The shaft 43^a serves to conduct the compressed gas and discharges into an opening 38^a formed in the lower part of the base 16^a. An outlet pipe 32^a provided with a check valve 33^a communicates with the opening 38^a. A suitable connection 46 is provided between the motor shaft 36^a and the impeller hub 34^a whereby the motor 22^a directly drives the impeller.

The impeller 11^a further includes a series of discs 111 formed of sheet metal or the like and surrounding the hub 34^a with substantial clearance. The discs 111 are preferably of like size and may be of substantially the same diameter as the part 35^a. The discs 111 are dished or pitched and the adjacent discs are pitched in opposite directions. The inner edge portions of the adjacent discs 111 abut and are connected at 112. The uppermost disc 111 is spaced from the lower side of the part 35^a. The discs 111 are shaped and related to have annular passages 113 between their opposing surfaces. The passages 113 extend from the interior of the assembly to the periphery of the impeller and decrease in thickness or capacity as they extend outwardly. Inner and outer rows of pins 114 and 115 serve to connect the several discs 111 and serve to attach the disc assembly to the impeller part 35^a. The inner pins 114 are tubular and are closed

at their lower ends. The outer pins 115 may be solid and carry spacers 116 which maintain the discs in the desired spaced relation. The passages 113 between the adjacent discs 111 are flared at their outer parts to have mouths 117. The upper ends of the tubular disc carrying pins 114 are open at the top of the impeller part 35^a.

The casing 12^a is substantially the same as the above described casing 12 comprising a main cup-like section 58^a closed at its upper end by a plate 59^a. The casing 12^a encloses the impeller 11^a with clearance and is independently rotatably supported in the housing 10^a. A bearing 118 mounts the lower part of the section 58^a on the shaft 43^a while a bearing 119 supports the plate 59^a on the impeller hub 34^a.

The drive 14^a is a differential drive between the casing 12^a and the impeller 11^a. The drive 14^a may be the same as the drive 14 described above. As illustrated, the drive 14^a includes a gear 78^a keyed or fixed to the casing 12^a and a larger gear 79^a fixed to the impeller shaft 43^a. A pair of connected gears 81^a and 82^a is mounted on the stub 80^a to rotate as a unit. The gear 82^a meshes with the gear 79^a and the gear 81^a meshes with the gear 78^a. The differential drive 14^a is preferably disposed below the casing 12^a within the wall 27^a.

The compressor includes port means or duct means for supplying the compressing liquid and the gas to the impeller 11^a and for handling the compressed gas. In the construction illustrated a pipe 120 delivers the compressing liquid to a port 121 in the wall of the housing member 18^a. A valve 122 may be provided to govern the flow through the port 121. A pipe 123 leads from the port 121 to an annular recess 124 in the top of the plate 59^a. Series of radially spaced ports 125 are provided in the plate 59^a to conduct fluid from the recess 124 to the interior of the casing 12^a. A sealing flange 126 is provided on the under side of the plate 59^a and is received in an annular groove 127 in the top of the impeller part 35^a. The flange 126 is arranged to direct the liquid to the tubular pins 114. The flange 126 is adjacent and spaced outwardly from the upper ends of the pins 114 and centrifugal force carries the liquid from the ports 125 to the upper ends of the pins 114. The pins 114 have lateral ports 128 for discharging into the passages 113. The ports 128 are vertically spaced and are faced outwardly to discharge the compressing liquid outwardly in the passages.

The compressing liquid thus delivered to the passages 113 discharges from the mouths 117 of the passages 113 into the casing 12^a. An annular deflector 129 is secured to the lower wall of the case member 58^a by rivets or pins 130. The deflector 129 is turned upwardly at its inner and outer edges to have its edge portions in adjacent relation to the lowermost disc 111. The deflector 129 is spaced from the lower wall of the section 58^a leaving a space 131. The liquid discharging from the mouths of the impeller passages 113 flows downwardly and then inwardly through the space 131 to the interior of the impeller assembly where it re-enters the passages 113.

Water or other liquid may be continuously supplied to the compressor by the pipe 120 and means is provided for continuously leading the used liquid from the compressor. This means includes an annular upstanding wall 132 on the section 58^a spaced between the hub 34^a and the interior of the assembly of discs 111. Longitu-

dinal ports 133 extend through the wall 132 and the lower wall of the section 58^a. The upper ends of the openings 133 are open to the interior of the impeller 11^a at the normal liquid level of the compressor so that the excess liquid runs down the ports. A plate 134 is secured to the upper end of the wall 27^a to direct the liquid from the ports 133 outwardly to the outer portion of the depression 26^a. A liquid discharge pipe 135 carries the liquid away from the depression 26^a.

The air or gas to be compressed is admitted to the housing 10^a by a pipe 136 communicating with the upper portion of the housing chamber 24^a. The gas is free to flow through the inner ports 125 to the interior of the casing 12^a. Vertical ports 137 extend through the impeller part 35^a and terminate at a trap flange 138 adjacent the upper end of the wall 132. The gas is thus admitted to the interior of the impeller 11^a and is entrained with the liquid discharging from the ports 128 moving outwardly through the passages 113. The gas is put under pressure by the liquid subjected to centrifugal action in the passages 113 and the compressed gas leaving the mouths 117 is caught in an annular groove 140 formed in the impeller part 35^a. Radial ports 141 extend from the groove 140 to the upper end of the opening 42^a to conduct the compressed gas to the upper end of the tubular shaft 43^a. The gas flows through the shaft 43^a to the opening 30 to discharge through the pipe 32^a.

The operation of the compressor illustrated in Figs. 5 and 6 is similar to the operation of the previously described form of the invention. Assuming that the impeller 11^a is driven by the motor 22^a and that water or other liquid is admitted through the pipe 123 at a suitable rate, the device operates to compress the gas admitted by the pipe 136. As described above, the liquid flows through the ports 125 to enter the upper ends of the tubular pins 14 and discharges from the ports 128. Centrifugal force carries the liquid outwardly through the passages 113. The gas from the chamber 24^a flows through the ports 125 and 137 to the interior of the impeller 11^a to be entrained in the liquid. The liquid moving outwardly through the passages 113 compresses the gas and the compressed gas discharges from the periphery of the impeller 11^a to be received in the groove 140. As described above, the compressed gas flows through the ports 141, the pipe 43^a and the opening 30 to the discharge pipe 32^a. The centrifugal action provides a differential in pressures in the casing 12^a and the liquid under high pressure at the peripheral part of the compression chamber returns through the space 131 to the interior of the impeller 11^a where it re-enters the passages 113. Thus there is a continuous recycling of the liquid.

The fluid discharging from the periphery of the impeller 11^a into the body of liquid rotating with the impeller 11^a acts on the casing 12^a to rotate the same. As in the foregoing form of the invention the energy required to increase the velocity of the liquid as it moves through the impeller passages 113 is expended by the liquid in rotating the casing 12^a. Further, the fluid friction of the fluid mass turning with the impeller aids in rotating the casing 12^a. The differential drive 14 transmits the rotation from the casing 12^a to the impeller 11^a and causes the casing to turn at a slower rate than the im-

peller. This action is the same as in the foregoing form of the invention.

Figure 7 illustrates a form of the invention embodying a hydraulic means 14^b for producing a differential in the speed of rotation of the impeller and the casing, and a governing means or unloading means X.

In the compressor shown in Figure 7 the hydraulic speed differential means 14^b replaces the gear drive 14, described above. The housing 10^b, the impeller 11^b, the casing 12^b, the port member 13^b and the port and conduit means for handling the liquid and gas are the same as the corresponding elements of the structure shown in Figures 1 to 4 inclusive, except for the differences described below.

The hydraulic means 14^b for causing a differential in the speed of rotation of the casing 12^b and the impeller 11^b includes ports 87^b and 89^b similar in character to the ports 87 and 89, but much greater in fluid capacity to provide for the return of liquid to the reservoir 83^b at a substantial rate. The means 14^b also provides for the delivery of a large volume of liquid from the reservoir 83^b to the valve member 13^b. A cup-like member 150 is secured in the reservoir 83^b in overlying relation to a sump 151 formed in the bottom wall of the reservoir. Ports 152 maintain communication between the reservoir 83^b and the sump 151. Similar ports 153 in the bottom of the member 150 put the interior of the member in communication with the sump 151. The casing 12^b has a central depending boss 154, which enters the member 150 with substantial clearance. The boss 154 carries a bearing 155, which assists in rotatably supporting the casing 12^b. The lower end of the boss 154 has a series of ports 156 of substantial aggregate fluid capacity for conducting the liquid from the member 150 to the interior of the boss. The boss 154 is hollow or tubular and its upper end communicates with the space 67^b in the port member 13^b. The port member 13^b has a plurality of spaced lateral ports 99^b, considerably larger than the above described ports 99, for conducting the cooled liquid from the space 67^b to the outer surface of the port member to be picked up by the rotating impeller 11^b.

The port system, or fluid handling system just described, is designed to handle a large volume of the compressing medium or liquid. This conducting of a large volume of the liquid, as it circulates to and from the reservoir 83^b, imposes a substantial load or drag on the casing 12^b causing the casing to rotate at a slower rate than the impeller 11^b. It is to be observed that the differential in the speed of rotation of the impeller 11^b and the casing 12^b depends upon the rate of circulation of the liquid from the interior of the casing 12^b to the reservoir 83^b and back to the reservoir.

The means X serves to regulate or govern the rate of flow of the liquid from the reservoir 83^b to the interior of the casing 12^b and thus serves to control the differential in the speed of rotation of the casing and the impeller 11^b and the compressing action of the device. The means X includes a port system in the impeller 11^b for handling the compressed gas after the compressor has reached a given or maximum output. This port system is an addition to the ports 52, 53, 54, 56 and 43^b described above, and includes an annular space or trap 158 in the impeller above the upper flange 51. The trap 158 serves to receive the compressed gas that overflows from the

pockets 51 and spills over the upper flange 57. Ports 159 extend inwardly through the impeller 11^b from the trap 158 to longitudinal ports 160 formed in the hub portion of the impeller. A socket 161 is provided in the lower end of the impeller 11^b and the ports 160 communicate with the upper end of the socket.

The means X further includes a plunger 162 movable longitudinally in the socket 161. A spring 163 is arranged against the under-side of the plunger 162 to urge the plunger upwardly to a retracted position. A stop flange 164 is provided on the shaft 43^b to limit the upward movement of the plunger 162 and to prevent the plunger from closing the lower ends of the ports 160. The lower end of the plunger 162 carries a valve part 165 exposed at the lower end of the socket 161. The valve part 165 is operable to restrict or close the liquid return ports 156 when the plunger 162 is moved downwardly.

The operation of the compressor illustrated in Figure 7 is substantially the same as in the previously described form of the invention. Under some conditions of use or operation, the compressing rate of the device may exceed a given or fixed value, in which case compressed gas overflows the pockets 51 and the upper flange 57 and spills into the space or trap 158. This compressed gas is received by the ports 159 and 160 and acts downwardly against the upper end of the plunger 162. When the pressure of this gas exceeds a given value it overcomes the spring 163 and the plunger 162 moves downwardly. The downward movement of the plunger may bring the valve part 165 to a position where it closes or substantially closes the ports 156. Upon a marked restriction or a closing of the ports 156, the load imposed on the casing 12^b, by reason of the circulation of liquid between the casing and the reservoir 83, is relieved or removed and the casing soon rotates at substantially the same speed as the impeller 11^b. With the casing 12^b rotating at substantially the same speed as the impeller 11^b the compressing action is reduced to a minimum or stops. Thus closing of the ports 156 by the action of the overflow gas pressure unloads the compressor. When the demand for the compressed gas is resumed or when conditions return to normal the gas pressure against the upper end of the plunger 162 lessens because of the leakage of gas from above the plunger and the spring 163 returns the plunger to its normal position where the ports 156 are open. This allows the circulation of liquid from the casing 12^b to the reservoir 83^b to be resumed and the load or drag is re-applied to the casing 12^b to provide the normal differential in the speed of rotation of the impeller and casing. The compressor illustrated in Figure 7 embodies a simple hydraulic means for producing a differential at the speed of rotation of the impeller and casing and a novel means for unloading or governing the compressor.

The present invention provides a compressor or vacuum pump that is quiet in operation and that operates efficiently with a minimum of power. The compressor utilizes the energy in the fluid discharged from the impeller to drive the surrounding casing which in turn is geared to the impeller so that the otherwise wasted energy is utilized to assist in rotating the impeller.

Having described only typical preferred forms and applications of my invention, I do not wish to be limited or restricted to the specific details herein set forth, but wish to reserve to myself

any variations or modifications that may appear to those skilled in the art or fall within the scope of the following claims.

Having described my invention, I claim:

1. A compressor or vacuum pump of the character described comprising a rotatable impeller having outwardly extending passages in which fluid is subjected to the effect of centrifugal action, said passages discharging the fluid from the impeller, means for conducting liquid and gas to the inner ends of said passages, means for rotating the impeller, a rotatable case enclosing the impeller and rotated by the fluid discharging from the impeller, a drive between the case and impeller whereby the case assists in rotating the impeller, means for conducting the gas from the case, and means for returning the liquid from the case to the first named means.
2. A compressor or vacuum pump of the character described comprising a rotatable impeller having passages in which fluid is subjected to the effect of centrifugal action, said passages discharging the fluid from the impeller, means for rotating the impeller, a rotatable case enclosing the impeller and rotated by the fluid discharging from the impeller, port means rotatable with the case for supplying fluid to the passages of the impeller, means for conducting gas to the port means, means for conducting liquid from the case to the port means, and means for conducting away the compressed gas leaving the passages.
3. A compressor or vacuum pump of the character described comprising a rotatable impeller having passages in which fluid is subjected to the effect of centrifugal action, inlet port means for supplying liquid and gas to said passages, said passages discharging the fluid from the impeller, means for rotating the impeller, a rotatable case around the impeller rotated by the fluid discharged from the impeller, means for conducting away the compressed gas discharged from said passages, and a differential drive between the case and impeller whereby the energy of the said discharging fluid assists in rotating the impeller.
4. In a machine of the character described, a case supported for rotation, a centrifugal type impeller rotatable in the case, means for admitting charges of gas and a heavier fluid to the impeller to be subjected to the effect of centrifugal action so that the gas is under increased pressure upon leaving the impeller, means for conducting the compressed gas from the impeller, the case receiving the fluid leaving the impeller and being rotated by said fluid, and a drive between the case and impeller whereby the case assists in rotating the impeller.
5. In a machine of the character described, a case supported for rotation, a centrifugal type impeller rotatable in the case, means for admitting charges of gas and a heavier fluid to the impeller to be subjected to the effect of centrifugal action so that the gas is under increased pressure upon leaving the impeller, means for conducting the compressed gas from the impeller, the case receiving the fluid leaving the impeller and being rotated by said fluid, means for returning the fluid from the case to the first named means for re-use, and a drive between the case and impeller whereby the case assists in rotating the impeller.
6. In a machine of the character described, a case supported for rotation, a centrifugal type impeller rotatable in the case, means rotatable with the case for discharging bodies of gas and a

heavier fluid to the impeller so that the gas is compressed by the effect of centrifugal action on the said fluid, means for conducting the compressed gas from the impeller to the exterior of the case, the case being rotated by the said fluid discharged from the impeller, and means producing a differential in the speed of rotation of the case and impeller whereby the impeller rotates relative to the first named means to receive said charges therefrom.

7. In a machine of the character described, a case supported for rotation, a centrifugal type impeller rotatable in the case, means rotatable with the case for discharging bodies of gas and a heavier fluid to the impeller so that the gas is compressed by the effect of centrifugal action on the said fluid, means for conducting the compressed gas from the impeller to the exterior of the case, the case serving to receive the said fluid discharged from the impeller and being rotated by the same, means directing the said fluid from the case to the first named means for re-delivery to the impeller, and means retarding rotation of the case so that the impeller rotates relative to said first named means to receive said charges.

8. In a machine of the character described, a case supported for rotation, a centrifugal type impeller rotatable in the case, means rotatable with the case for discharging bodies of gas and a heavier fluid to the impeller so that the gas is compressed by the effect of centrifugal action on the said fluid, means for conducting the compressed gas from the impeller to the exterior of the case, the case serving to receive the said fluid discharged from the impeller and being rotated by the same, means directing the said fluid from the case to the first named means for re-delivery to the impeller, and means retarding rotation of the case so that the impeller rotates relative to said first named means to receive said charges, the last named means comprising a differential power transmitting drive between the case and the impeller whereby the said fluid in rotating the case assists in rotating the impeller.

9. In a machine of the character described, a rotatable centrifugal impeller, means supplying liquid and gas to the impeller to be discharged therefrom, a rotatable case around the impeller rotated by the fluid discharged from the impeller means for conducting the compressed gas from the case, and means for conducting liquid from the case.

10. In a machine of the character described, a rotatable centrifugal impeller, means supplying liquid and gas to the impeller to be discharged therefrom, means for rotating the impeller, a rotatable case around the impeller rotated by the fluid discharged from the impeller, a drive between the case and impeller transmitting force from the case to the impeller, means for conducting the compressed gas from the case, and means for returning the liquid from the case to the first named means.

11. In a machine of the character described, a case supported for rotation, a centrifugal type impeller rotatable in the case, means rotatable with the case for discharging bodies of gas and a heavier fluid to the impeller so that the gas is compressed by the effect of centrifugal action on the said fluid, means for conducting the compressed gas from the impeller to the exterior of the case, the case serving to receive the said fluid discharged from the impeller and being rotated by the same, means directing the said fluid from the

case to the first named means for re-delivery to the impeller, and cooling means withdrawing a stream of said fluid from the said first named means, reducing the temperature of the fluid thus withdrawn and then returning the cooled fluid to the said first named means.

12. In a machine of the character described, a rotatable centrifugal impeller, means for supplying gas and a heavier fluid to the impeller to be discharged therefrom, a rotatable case enclosing the impeller to receive the fluid leaving the impeller and rotated by the fluid put into motion by the impeller, a part rotatable with the case having a passage conducting said heavier fluid from the periphery of the impeller to the said means for redelivery to the impeller and outlet means for conducting away the gas discharged from said passages.

13. A compressor or vacuum pump comprising a rotatable impeller having outwardly directed passages discharging at its periphery and having ports leading inwardly from its periphery, means for rotating the impeller, a case supported for rotation and enclosing the impeller to receive the fluid discharged from said passages and to be rotated by the fluid put into motion by the impeller, a member rotatable with the case and arranged within the impeller, the member having fluid ports adapted to communicate with the said passages, and gas ports adapted to communicate with the passage, means delivering gas to the gas ports, means in the case circulating fluid from the peripheral part of the case to said fluid ports of the member, a differential drive between the case and the impeller causing the case to rotate at a slower speed than the impeller whereby said passages pick up alternate charges of fluid and gas from said fluid ports and gas ports, the gas being compressed in said passages and discharged at the periphery of the impeller where it is received by said inwardly directed ports, and means conducting the compressed gas from the impeller to the exterior of the case.

14. A compressor or vacuum pump comprising a rotatable impeller having outwardly directed passages discharging at its periphery and having ports leading inwardly from its periphery, means for rotating the impeller, a case supported for rotation and enclosing the impeller to receive the fluid discharged from said passages and to be rotated by the fluid put into motion by the impeller, a member rotatable with the case and arranged within the impeller, the member having fluid ports adapted to communicate with the said passages, and gas ports adapted to communicate with the passage, means delivering gas to the gas ports, means in the case circulating fluid from the peripheral part of the case to said fluid ports of the member, a differential drive between the case and the impeller causing the case to rotate at a slower speed than the impeller whereby said passages pick up alternate charges of fluid and gas from said fluid ports and gas ports, the gas being compressed in said passages and discharged at the periphery of the impeller where it is received by said inwardly directed ports, means conducting the compressed gas from said inwardly directed ports, a stationary housing enclosing the case, fluid cooling means in the housing, and means conducting a stream of the fluid from within the case to the cooling means and back into the case.

15. A compressor or vacuum pump of the character described comprising a rotatable impeller having passages in which fluid is subjected to the

effect of centrifugal action, means supplying gas and a heavier fluid to said passages, said passages discharging the fluid from the impeller, the impeller comprising a plurality of disks connected in spaced relation to define said passages, means for rotating the impeller, a rotatable case enclosing the impeller and rotated by the fluid discharging from the impeller, outlet means for conducting away the gas discharged from said passages, means for conducting the heavier fluid from the case to the first named means for re-delivery to said passages, and a drive between the case and impeller whereby the case assists in rotating the impeller.

16. A compressor or vacuum pump of the character described comprising a rotatable impeller having passages in which the fluid is subjected to the effect of centrifugal action, said passages discharging the fluid from the impeller, means for rotating the impeller, a rotatable case enclosing the impeller and rotated by the fluid put into motion by the impeller, the impeller having port means for admitting gas and a heavier fluid to its passages, valve controlled means supplying said heavier fluid to the port means, means for conducting the gas to the port means, means in the case circulating the heavier fluid from the periphery of the case to the inner ends of said passages, means discharging the excess heavier fluid from the case, and a drive between the case and impeller whereby the case assists in rotating the impeller.

17. In a machine of the character described, a case supported for rotation, a centrifugal type impeller rotatable in the case, means rotatable with the case for discharging bodies of gas and a heavier fluid to the impeller so that the gas is compressed by the effect of centrifugal action on the said fluid including a member secured to the case and provided with circumferentially spaced ports in its periphery for discharging said heavier fluid into the passages and peripheral ports spaced between the first mentioned ports for discharging the gas into the passages, means for conducting the compressed gas from the impeller to the exterior of the case, the case being rotated by the said fluid discharged from the impeller, and means producing a differential in the speed of rotation of the case and impeller whereby the impeller rotates relative to the first named means to receive said charges therefrom.

18. A compressor or vacuum pump comprising a rotatable impeller having outwardly directed passages discharging at its periphery and having ports leading inwardly from its periphery, the ports being enlarged at their outer ends to form pockets for the reception of the compressed gas, means for rotating the impeller, a case supported for rotation and enclosing the impeller to receive the fluid discharged from said passages and to be rotated by the fluid put into motion by the impeller, a member rotatable with the case and arranged within the impeller, the member having fluid ports adapted to communicate with the said passages, and gas ports adapted to communicate with the passage, means delivering gas to the gas ports, means in the case circulating fluid from the peripheral part of the case to said fluid ports of the member, a differential drive between the case and the impeller causing the case to rotate at a slower speed than the impeller whereby said passages pick up alternate charges of fluid and gas from said fluid ports and gas ports, the gas being compressed in said passages and discharged at the periphery of the impeller where it is received

by said inwardly directed ports, and means conducting the compressed gas from the impeller to the exterior of the case.

19. A compressor or vacuum pump of the character described comprising a rotatable impeller having passages in which fluid is subjected to the effect of centrifugal action, said passages discharging the fluid from the impeller, means for rotating the impeller, a rotatable case enclosing the impeller and rotated by the fluid discharging from the impeller, gas inlet means, liquid inlet means receiving liquid from the case, a ported member rotatable with the case receiving the gas and liquid from the inlet means and operating to deliver the same to said passages upon a differential in the speed of rotation of the impeller and case, and means retarding the case to cause said speed differential.

20. A compressor or vacuum pump of the character described comprising a rotatable impeller having passages in which fluid is subjected to the effect of centrifugal action and by which the fluid is discharged from the impeller, gas inlet means, means for rotating the impeller, a rotatable case enclosing the impeller and rotated by the fluid discharging from the impeller, a ported member rotatable with the case operable to deliver said gas and a heavier fluid to said passages upon a differential in the speed of rotation of the impeller and case, and means retarding the case to cause said speed differential, said means including a source of such heavier fluid external of the case, port means in the case conducting the heavier fluid from said source to the ported member to impose a drag on the case and an outlet for said heavier fluid.

21. A compressor or vacuum pump of the character described comprising a rotatable impeller having passages in which fluid is subjected to the effect of centrifugal action and by which the fluid is discharged from the impeller, gas inlet means, means for rotating the impeller, a rotatable case enclosing the impeller and rotated by the fluid discharging from the impeller, a ported member rotatable with the case receiving the gas from said inlet means and operable to deliver the gas and a heavier fluid to said passages upon a differential in the speed of rotation of the impeller and case, and means retarding the case to cause said speed differential including a container for said heavier fluid external of the case, and port means in the case circulating said heavier fluid from the case to the container and from the container to the ported member to impose a load on the case.

22. A compressor or vacuum pump of the character described comprising a rotatable impeller having passages in which fluid is subjected to the effect of centrifugal action and by which the fluid is discharged from the impeller, gas inlet means, means for rotating the impeller, a rotatable case enclosing the impeller and rotated by the fluid discharging from the impeller, a ported member rotatable with the case receiving the gas from the inlet means and operable to deliver the gas and a heavier fluid to said passages upon a differential in the speed of rotation of the impeller and case, and means retarding the case to cause said speed differential, including a container for said heavier fluid external of the case, port means in the case circulating said heavier fluid from the case to the container and from the container to the ported member to impose a load on the case, and means controlling the rate of said circulation of said heavier fluid to control the rate of action of the compressor.

23. A compressor or vacuum pump of the character described comprising a rotatable impeller having passages in which fluid is subjected to the effect of centrifugal action and by which the fluid is discharged from the impeller, gas inlet means; means for rotating the impeller, a rotatable case enclosing the impeller and rotated by the fluid discharging from the impeller, a ported member rotatable with the case receiving the gas from said inlet means and operable to deliver the gas and a heavier fluid to said passages upon a differential in the speed of rotation of the impeller and case; and means retarding the case to cause said speed differential including a container for said heavier fluid external of the case, port means in the case circulating said heavier fluid from the case to the container and from the container to the ported member to impose a load on the case, and means for governing the compressor or pump comprising a valve for controlling said port means, and means for subjecting the valve to fluid pressure developed in said passages to operate when said pressure reaches a given value.

24. A compressor or vacuum pump of the character described comprising a rotatable impeller

having passages in which fluid is subjected to the effect of centrifugal action by which the fluid is discharged from the impeller, gas inlet means, means for rotating the impeller, a rotatable case enclosing the impeller and rotated by the fluid discharging from the impeller, a ported member rotatable with the case receiving the gas from said inlet means and operable to deliver the gas and a heavier fluid to said passages upon a differential in the speed of rotation of the impeller and case; and means retarding the case to cause said speed differential including a container for said heavier fluid external of the case, port means in the case circulating said heavier fluid from the case to the container and from the container to the ported member to impose a load on the case, and means for governing the compressor or pump comprising a valve for controlling said port means, and means for subjecting the valve to fluid pressure developed in said passages to operate when said pressure reaches a given value, the last-named means comprising a port system leading from the periphery of the impeller to the valve.

ERNEST R. HUNTLEY.
